CLAIM

The ornamental design for the microcatheter guiding device, as shown and described.

DESCRIPTION

FIG. 1 is a rear perspective view of the microcatheter guiding device of the present invention; and

FIG. 2 is a rear view thereof; and

FIG. 3 is a front view thereof; and

FIG. 4 is a right side view thereof; and

FIG. 5 is a left side view thereof; and

FIG. 6 is top view thereof; and,

FIG. 7 is a bottom view thereof.
